(57) **CLAIM**

The ornamental design for a drawing tablet, as shown and described.

DESCRIPTION

FIG. 1 is a front, top perspective view of a drawing tablet; FIG. 2 is a rear, bottom perspective view thereof;

FIG. 3 is a rear, left perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

Any shading or cross-hatching are no features of the design but are utilized to illustrate the surface contours of the drawing tablet design in the drawings. The broken lines illustrate portions of the drawing tablet and form no part of the claimed design.

1 Claim, 9 Drawing Sheets
